[57] ABSTRACT

[52] U.S. Cl. 91/490, 91/491

An improved radial piston pump or motor of the type wherein a rotor is rotatably mounted upon a pintle valve spindle eccentrically fixed within a cylindrical race, the rotor having hollow radial spokes communicated with passages of the pintle valve and reciprocably mounting hollow pistons thereon having shoes riding against the inside of the race. Each piston is of unique two-part construction preferably including a bronze shoe such that the race against which it rides may be advantageously of steel. In addition, the shoe of each piston is preferably provided with a flange which rides upon retaining protrusions of the race.

**PISTON AND RETAINING ASSEMBLIES FOR A
RADIAL PISTON PUMP OR MOTOR**

BACKGROUND OF THE INVENTION

Radial piston pumps or motors are variously employed in hydrostatic applications for converting mechanical torque to hydraulic pressure or hydraulic pressure to mechanical torque. Such a power transfer device is disclosed, for example, in U.S. Pat. No. 3,274,946 which issued Sept. 27, 1966 to E. E. Simmons.

Briefly, the device includes a pintle valve spindle coaxially mounted in fixed position within a housing, and a cylindrical race fixedly mounted therein eccentrically about the spindle. A rotor is rotatably received upon the spindle and provided with a plurality of circumferentially spaced spokes projecting radially therefrom. The spokes are hollow so as to define radial passages which are arranged to communicate with valve passages of the spindle during rotation of the rotor thereon.

The outer end of each spoke is provided with an annular spherical bearing member which serves to mount a hollow cylindrical piston for reciprocation thereon, the interior of the piston communicating with the passage of the spoke. The head end of each piston is formed as a shoe which rides against the inside of the race during rotor rotation. For details as to the operation of such a device, reference may be had to the previously referenced patent.

In a power transfer device of the class outlined above, it has been the usual practice to fabricate the race from a material such as bronze and to integrally fabricate each piston from a material such as steel. This has not resulted in a particularly compatible running relationship between the piston shoes and race which has thereby limited the life of the parts and detracted from trouble-free service of the device. Because of the one-piece construction of the piston it has been relatively difficult to machine the inner diameter of the skirt portion thereof with accuracy. Further, the one-piece construction of the piston is susceptible to non-uniform flexing of its skirt portion which detracts from the uniformity of clearance that can be maintained between the skirt interior and bearing portion of a spoke and thereby limits control of oil leakage therebetween.

In addition, with a great number of conventional radial piston power transfer designs, means are not provided to positively retain the pistons in close proximity to the inside control surface of the race to prevent the pistons from banging into the surface during initial startup of the device.

SUMMARY OF THE INVENTION

The present invention relates to a radial piston power transfer device for use as a hydrostatic pump or motor which is characterized by improved piston and retaining assemblies.

It is a general object of the present invention to provide a device of the class described having improved troublefree service.

Another object of the invention is the provision of an improved piston assembly for a radial piston power transfer device which is arranged to provide a more compatible longer life running relationship between the shoe portion of the piston and control surface of the race.

It is yet another object of the present invention to provide a two-part piston assembly for a radial piston power transfer device, which will facilitates easy accurate machining of the inner diameter of the skirt portion of the piston and uniform flexing thereof throughout its length in order to afford improved leakage control of oil between the piston and spoke bearing of the rotor of the device.

A further object of the invention is the provision of a piston assembly of the class described having a flanged head shoe portion for riding upon retaining protrusions of the race to maintain the shoe portion in intimate contact with the control surface of the race such that during startup of the device banging of the piston assembly into the control surface of the race (due to centrifugal forces or the onset of hydraulic pressure) is prevented.

BRIEF DESCRIPTION OF THE DRAWING

The single FIGURE is a sectional view through an improved radial piston power transfer device in accordance with the present invention.

**DETAILED DESCRIPTION OF A PREFERRED
EMBODIMENT OF THE INVENTION**

Referring now to the drawing in detail, there is shown a radial piston hydrostatic power transfer device 11 which may be employed as a pump or motor to convert mechanical torque to hydraulic pressure or hydraulic pressure to mechanical torque. In basic respects the device is similar to that disclosed in the previously referenced U. S. Pat. No. 3,274,946, and therefore the device 11 is only described hereinafter to the extent necessary to facilitate a full understanding of the salient aspects of the present invention.

The power transfer device 11 includes a rotor assembly 12 rotated about and carried in intimate contact with a pintle valve spindle 13 fixedly secured as by means of cap screws 14 to one end cover 16 of a generally cylindrical housing assembly 17, preferably in coaxial relation thereto. The complete housing assembly is preferably formed by the end cover 16, an opposed end cover 18, and an interposed cylindrical portion 19 bolted therebetween.

The rotor assembly 12 comprises a cylindrical hub 21 rotatably concentrically mounted upon the spindle 13 and axially positioned and retained as by means of thrust washers 22 and 23 respectively interposed between one end face of the hub and a shoulder of the spindle and between the opposite end face of the hub and the housing cover 18.

A plurality of circumferentially spaced spokes 24 are secured to the hub, as by welding, to project radially outward therefrom, such spokes being hollow to define radial passages 26 in registry with apertures 27 through the hub in communication with passages 28 of the pintle valve spindle 13 during rotation of the rotor assembly thereon. On the outer end of each spoke 24 there is secured an annular spherical bearing member 29 which serves to mount a hollow piston assembly 31, in accordance with the present invention, for reciprocation thereon.

The head ends of the piston assemblies ride against a cylindrical control surface of a race 32 mounted within housing assembly 17 eccentrically about the rotor assembly 12 which thereby serves to reciprocate

the pistons upon the spokes during rotation of the rotor upon the pintle valve spindle.

Considering now the particularly salient aspects of the present invention, it is to be noted that heretofore it has been the practice to fabricate the race 32 from a material such as bronze, and to integrally fabricate each piston as a single part from a material such as steel. This has not resulted in a particularly compatible running relationship between the pistons and the race in that the bronze race is excessively susceptible to denting and scuffing by the radially reciprocating steel pistons.

Moreover, with a one-part piston it is relatively difficult to accurately machine the inner diameter of the skirt portion thereof for close fitting reciprocating engagement with the bearing members 29 of the spokes 24. Furthermore, a one-part piston gives rise to non-uniform flexing along the length of the skirt portion which thereby detracts from the uniformity of clearance and control of oil leakage that can be maintained between the inner diameter of the skirt portion and the spoke bearing member.

Accordingly, in accordance with the improvements of the present invention each piston assembly 31 is of novel two-part construction including a hollow cylindrical skirt portion 33 and a separate shoe 34 sealably secured to one end of the skirt portion to define the head end of the piston which rides against the control surface of the race 32.

Sealed securance between the parts is preferably facilitated by forming the shoe 34 with a depending annular flange 36 having an outwardly flared lip at its end, and an annular groove 37 circumscribing the flange and radially inwardly undercut at its base. The skirt portion 33 is formed at one end with a complementary coaxially projecting annular flange 38 with an inwardly flared lip at its end, and an undercut annular shoulder 39 inwardly of the flange.

The shoe flange 36 conformably engages the undercut shoulder 39 of the skirt portion and the skirt flange 38 conformably engages the shoe groove 37 to provide a sealed joint between the parts. It is particularly important to note that the shoe 34 is of a material such as bronze while the race 32 is of a material such as steel. The running relationship between the bronze capped piston assemblies 31 and steel race 32 has improved compatibility and provides relatively trouble-free service.

Of course, by virtue of the skirt portion 33 being a separate cylindrical part, its inner diameter may be accurately machined with relative ease. The sealed joint between the shoe 34 and skirt portion 33 permits uniform flexing of the latter throughout its length without disruption of the seal.

As another important feature of the invention, the shoe 34 preferably extends radially outward beyond the outer periphery of the skirt portion 33 to define an outwardly flared annular flange 41. Such flange rides against protrusions 42 of the race 32 which serve to positively radially retain the piston shoes 34 in intimate contact with the control surface of the race to prevent centrifugal banging of the shoes against the race during startup of the power transfer device 11.

More particularly, the race 32 is preferably of a U-shaped cross section formed of a control surface defining ring 43 and a pair of coaxially spaced annular covers 44 secured to the opposite ends of the ring to ex-

tend radially inward therefrom. The retaining protrusions 42 are then provided as annular lips which project coaxially inward from the inner faces of the covers 44 in radially inwardly spaced relation to the inner control surface of the ring 43 of the race 32. The grooves 46 thereby defined between the protrusions 42 and inner surface of ring 43 serve to receive the flange 41 of each piston assembly 31 such that the shoe 34 thereof is radially retained in intimate contact with the control surface of the race.

Although the invention has been hereinbefore described and illustrated in the accompanying drawing with respect to a single preferred embodiment, it will be appreciated that numerous modifications and changes may be made therein without departing from the true spirit and scope of the invention, and thus it is not intended to limit the invention except by the terms of the appended claims.

What is claimed is:

1. In a radial piston hydrostatic power transfer device of the type including a pintle valve spindle fixedly secured within a housing, a rotor rotatably mounted upon the spindle and having a plurality of circumferentially spaced radially projecting spokes with radial passages communicating with passages of the pintle valve spindle, each spoke having an annular spherical bearing member at its outer end, and an annular race fixedly secured within the housing eccentrically about the rotor, the improvement comprising a plurality of two-part piston assemblies reciprocally mounted upon said spokes, each of said piston assemblies having a hollow cylindrical skirt portion with an inner surface in bearing relation to the bearing member of one of said spokes and a separate shoe sealably secured to an end of said skirt portion and engaging a cylindrical control surface of said race, further defined by said shoe of each of said piston assemblies having a depending annular flange having an outwardly flared lip at its end and an annular groove circumscribing said flange and radially inwardly undercut at its base, said skirt portion of each of said piston assemblies having a complementary coaxially projecting annular flange with an inwardly flared lip at its end and an undercut annular shoulder inwardly thereof, said flange of said shoe conformably engaging said shoulder of said skirt portion and said flange of said skirt portion conformably engaging said groove of said shoe.

2. The combination of claim 1, further defined by said shoe of each of said piston assemblies being of bronze and said race being of steel.

3. In a radial piston hydrostatic power transfer device of the type including a pintle valve spindle fixedly secured within a housing, a rotor rotatably mounted upon the spindle and having a plurality of circumferentially spaced radially projecting spokes with radial passages communicating with passages of the pintle valve spindle, each spoke having an annular spherical bearing member at its outer end, and an annular race fixedly secured within the housing eccentrically about the rotor, the improvement comprising a plurality of two-part piston assemblies reciprocably mounted upon said spokes, each of said piston assemblies having a hollow cylindrical skirt portion with an inner surface in bearing relation to the bearing member of one of said spokes and a separate shoe sealably secured to an end of said skirt portion and engaging a cylindrical control surface of said race, further defined by retaining means

positively radially retaining said shoes of said piston assemblies in intimate contact with said control surface of said race, further defined by said shoe of each piston assembly extending radially beyond the outer periphery of said skirt portion thereof to define an outwardly flared annular flange, said race having annular protrusions in radially spaced relation to said control surface of said race defining annular retaining grooves between said protrusions and said control surface, said outwardly flared flanges of said piston assemblies engaging said retaining grooves.

4. The combination of claim 3, further defined by said shoe of each of said piston assemblies having a depending annular flange having an outwardly flared lip

5 at its end and an annular groove circumscribing said flange and radially inwardly undercut at its ase, said skirt portion of each of said piston assemblies having a complementary coaxially projecting annular flange with an inwardly flared lip at its end and an undercut annular shoulder inwardly thereof, said flange of said shoe conformably engaging said shoulder of said skirt portion and said flange of said skirt portion conformably engaging said groove of said shoe.

10 5. The combination of claim 4, further defined by said shoe of each of said piston assemblies being of bronze and said race being of steel.
